UNITED STATES PATENT OFFICE.

MITTIE MASON, OF WASHINGTON, DISTRICT OF COLUMBIA.

COVER FOR LATRINE-SEATS.

1,313,236.

Specification of Letters Patent. Patented Aug. 12, 1919.

Application filed April 2, 1917. Serial No. 159,290.

To all whom it may concern:

Be it known that MITTIE MASON, a citizen of the United States of America, residing at Washington, in the District of Columbia, 5 has invented certain new and useful Improvements in Covers for Latrine-Seats, of which the following is a specification.

This invention relates to new and useful improvements in sanitary covers for latrine seats and has for its object to provide a seat cover which while susceptible of being cheaply manufactured and adapted to afford a comfortable seat is equipped for positive attachment to a seat and consequently is 10 not liable to be casually moved thereon or displaced.

The invention will be fully understood from the following description and claims when the same are read in connection with 20 the drawings accompanying and forming part of this specification, in which:

Figure 1 is a plan view of a device constructed in accordance with my invention;

Fig. 2 is a section therethrough as seen 25 on the line 2—2 of Fig. 1, showing the wire in place;

Fig. 3 is a section through a seat having my cover applied thereto, parts of the cover being shown in edge elevation;

Fig. 4 is a sectional plan view of a slightly 30 modified form of the invention;

Fig. 5 is a section therethrough as seen on the line 5—5 of Fig. 4; and

Fig. 6 is a section as seen on the line 6—6 35 of Fig. 4.

Referring by numeral to said drawings and more particularly to Figs. 1—3 thereof;

1 is my novel seat cover. This cover consists of two strips 2 and 3 formed preferably of tissue or other similar paper which strips while as shown oval in design may be of any shape to conform to the shape of the seat. Formed integral with the outer edges of said strips at intervals thereon are attaching tabs 4. The tabs of the two strips are glued, pasted or otherwise similarly secured together and arranged between each pair of opposed tabs is a fine thin wire 5, the latter being looped and extended from the free ends of the tabs to a point between the strips 2 and 3 where its bight rests, as clearly shown in Fig. 1 of the drawing. As shown in the drawing I preferably provide four tabs on each strip, but a greater number 50 may be provided, if desired, and the

wires 5 are positioned about centrally of the tabs and extend the full length of the same.

In applying the cover to use, the same is first applied flatly on the seat whereupon the tabs are bent downwardly to engage 60 around the edges and below the seat. The very fine non-elastic wires 5 in the tongues 4 will enable the latter to be readily bent and when so disposed will positively hold said tabs and correspondingly the cover in 65 position on the seat. The wires 5 being very thin and fine will not interfere with the use of the seat and when one use is had of the cover, the same may be quickly and readily removed and thrown away. 70

In the manufacture of these covers I prefer to have same folded longitudinally in half and then transversely in half so as to form a neat, small device which may be readily dispensed from a receptacle or the 75 like. If desired, these covers may be dispensed from a coin controlled machine or from a free dispensing apparatus, according to the place in which same are used.

In Figs. 4, 5, and 6 I have shown a 80 slightly modified form of the invention wherein a strip 6 designed to conform to the outline of the seat and form a cover therefor is provided at various points thereon with integral tabs 7. These tabs are of 85 considerable length and are doubled upon themselves and glued, pasted or otherwise secured together. Between the doubled portions of the tabs are positioned fine, non-elastic wires 8, as in the first-mentioned 90 form. The distinction between this form and the first-mentioned form is that the former comprises two sheets of paper, whereas the modified form is composed of a single sheet, the tabs being doubled upon themselves to hold the wires in position. 95

It will be gathered from the foregoing that when the tabs of my novel cover are bent about the outer edge of a seat, after the manner shown in Fig. 3, they will positively 100 hold the cover on the seat and against casual movement or displacement.

Having thus described my invention, what I claim and desire to secure by Letters Patent, is:—

1. As a new article of manufacture, a latrine seat cover, comprising a body having a central opening, tabs integral with and extending laterally outward from the body; each tab having two thicknesses of material, 110

and fine non-elastic wires secured in the tabs between the thicknesses of material thereof, for the purpose set forth.

2. As a new article of manufacture, a latrine seat cover comprising an apertured body and lateral tabs thereon and fine non-elastic wires carried by the tabs.

3. As a new article of manufacture, a latrine seat cover, comprising a body having a central opening, tabs integral with and extending laterally outward from the body;

each tab having two thicknesses of material, and a loop-shaped fine non-elastic wire secured in each tab between the thicknesses of material thereof and having its ends at the 15 outer end of the tab and its bight adjacent to the central opening.

In testimony whereof I affix my signature in the presence of a witness.

MITTIE MASON.

Witness:

BENNETT S. JONES.
